UNITED STATES PATENT OFFICE.

FRED A. HELFRECHT, OF BERKELEY, CALIFORNIA.

DESIGN FOR A CASING FOR HOLDING COUNTING DISKS.

Application filed March 16, 1921. Serial No. 452,762. Term of patent 3½ years.

To all whom it may concern:

Be it known that I, FRED A. HELFRECHT, a citizen of the United States, residing in the city of Berkeley, county of Alameda, State of California, have invented a new, original, and ornamental Design for a Casing for Holding Counting Disks, of which the following is a specification, reference being had to the accompanying drawing, forming part thereof.

Fig. 1 is a perspective view of the tabulator casing.

Fig. 2 is an edge view of the same.

I claim:

The ornamental design for a casing for holding counting disks, as shown.

FRED A. HELFRECHT.

Witnesses:

W. L. BOHANNON,
W. P. WOOLSEY.
